[57] CLAIM

The ornamental design for a bathtub for invalids or the like, as shown and described.

DESCRIPTION

FIG. 1 is a perspective view taken from the top, front and right side of a bathtube for invalids or the like showing our new design;

FIG. 2 is a front elevational view thereof;

FIG. 3 is a top plan view thereof;

FIG. 4 is a cross-sectional view taken on line 4—4 of FIG. 3;

FIG. 5 is a cross-sectional view taken on line 5—5 of FIG. 3;

FIG. 6 is a cross-sectional view taken on line 6—6 of FIG. 3;

FIG. 7 is a cross-sectional view taken on line 7—7 of FIG. 3; and,

FIG. 8 is a top plan view of a second embodiment thereof.

The fragmentary broken line representations of walls in FIG. 1 are for the purpose of illustration only and form no part of the claimed design.

FIG. 1
